[57] CLAIM

The ornamental design for a brow contouring sun visor, substantially as shown and described.

DESCRIPTION

FIG. 1 is a top plan view of a sheet cut to form a brow contouring sun visor, showing my new design.

FIG. 2 is a side view of said sheet.

FIG. 3 is a top perspective view of said sheet formed to a brow contouring sun visor, showing my new design. FIG. 4 is a front perspective view of the visor of FIG. 3. Some of the band slots have been omitted for convenience of illustration.

FIG. 5 is a side view in elevation of the visor shown in FIG. 3.

FIG. 2

FIG. 3

FIG. 4
